(57) **CLAIM**

The ornamental design for a notebook computer, as shown and described.

DESCRIPTION

FIG. 1 is a perspective view of a notebook computer showing our new design;

FIG. 2 is a front view thereof;

FIG. 3 is a left side view thereof;

FIG. 4 is a right side view thereof;

FIG. 5 is a top view thereof;

FIG. 6 is an enlarged view thereof the portion, labeled '6' of FIG. 1;

FIG. 7 is a perspective view thereof showing the palmrest closed;

FIG. 8 is a top view thereof showing the palmrest closed;

FIG. 9 is a cross-sectional view taken along line 9-9 in FIG.

8 with the internal parts being omitted; and,

FIG. 10 is an enlarged view thereof the portion, labeled '10' of FIG. 9.

The rear and bottom views are omitted because they are unornamented and form no part of the claimed design. The broken lines illustrate portions of the notebook computer and form no part of the claimed design.
